UNITED STATES PATENT OFFICE.

ALBERT E. GREENE, OF MEDINA, WASHINGTON.

ELECTRIC-FURNACE VOLTAGE CONTROL.

Continuation of applications Serial No. 207,966, filed January 3, 1913; Serial No. 157,931, filed March 28, 1917; and Serial No. 322,298, filed September 8, 1919. This application filed May 23, 1923. Serial No. 640,932.

My present invention relates to the voltage control apparatus for electric furnaces and processes for operating the same. My invention relates particularly to certain 5 kinds of low voltage transformers for use in conjunction with standard voltage transformers furnishing current to the electrodes of electric furnaces and to the combination of these special transformers with standard 10 transformers in connection with electric furnaces for changing, controlling and regulating the voltage applied to the furnace electrodes.

In my co-pending applications, Serial No. 15 207,966, filed January 3, 1913, and Serial No. 157,931, filed March 28, 1917, and Serial No. 322,298, filed Sept. 8, 1919, I have described and claimed certain improvements in the combination of transformers and electric 20 furnaces, and my present invention relates to improvements of the same kind. My present application is a continuation of those 25 applications above mentioned.

Heretofore in making provision for changing the voltage on electric furnaces it has 30 been customary to have the power transformers constructed in a special manner with taps or other connections so that the voltage applied to the furnace electrodes can be varied to meet the particular requirements. This has been done in a number of cases. For example, the primary windings of the 35 transformers are provided with taps so that the number of turns connected between the power lines may be changed and therefore the induced secondary voltage may be correspondingly varied. Or in other instances where three transformers have their primaries connected to a three-phase power line, provision has been made to change the 40 connections of the primaries from delta to star and thus change the induced secondary voltage applied to the electrodes. In other cases the secondary windings of the transformers 45 are provided with coils which may be connected in either series or parallel relation as more particularly described in my application for Patent 157,931, filed March 28, 1917. Where large furnaces are used the 50 transformers must be of large power capacity. The arrangements just mentioned involve the construction of very special transformers and such transformers are usually very 55 expensive and require considerable time for their construction and they are also made

for such special voltage as not to be serviceable for general power work.

But my present invention has for one of its objects the combination of a special low voltage transformer and a standard power 60 transformer in order to provide a simple means of changing voltage applied to the furnace electrodes. This special low voltage transformer is a voltage regulating transformer with independent or connected primary and secondary windings designed to take current from the secondary side of the power transformers and to add to or subtract from the voltage furnished by those standard power transformers. This combination has many advantages and it makes 65 possible the use of standard power transformers which take power from a high voltage power line on their primary side and furnish current at a standard low voltage 70 such as 110 volts or 220 volts or other standard low voltage.

In the operation of electric arc steel furnaces for melting and refining steel the range of voltage required between the electrodes of 80 a three-electrode, three-phase furnace ranges from about 80 volts up to about 140 volts and sometimes lower or higher than these voltages. Power transformers are usually equipped with secondary windings to furnish 85 110 or 220 volts. In case of the standard power transformer furnishing 110 volts, my present invention contemplates using a special low voltage transformer to raise or lower this 110 volts to the desired limits. 90 For example, I may use a special transformer which will add 30 volts to the 110 volts and thereby provide 140 volts between each pair of the three-phase conductors leading to the electrodes. And I may also operate this 95 same transformer to subtract 30 volts from the 110 volts and thus supply 80 volts to the electrodes. I may provide this special low voltage transformer, which may be called a booster transformer, with intermediate taps 100 so that a voltage less than 30 volts may be added to or subtracted from the secondary voltage supplied by the standard power transformer. For example, I may provide the booster transformer with taps and windings 105 so that it will boost the voltage from 110 to 120, or from 110 to 130, that is by adding 10 volts or by adding 20 volts to the standard 110 volts secondary voltage. Also I may reverse the direction of the current 110

through primary winding of the booster transformer without change of secondary connection so as to subtract 10 volts or 20 volts from the secondary voltage of 110. These are special features of my present invention.

My invention contemplates also constructing and combining a booster transformer so as to have its secondary windings in series with the conductors leading to the furnace electrodes, and at the same time have its primary windings connected in one way or another between the secondary terminals of the standard voltage transformers. Thus for example, my invention contemplates furnishing power to three electrodes of a three-phase arc furnace from power transformers connected to give 110 volts between secondary lines. That is 110 volts between each pair of the three conductors leading to the furnace electrode, and in this combination I insert a booster transformer so that each secondary winding of the booster transformer is in series with a conductor to an electrode, and each primary winding of the booster transformer would be connected to a secondary terminal of the standard power transformers.

One feature of my present invention relates to the means of changing the voltage of the booster transformer and this may be accomplished by providing the secondary windings of the booster transformers with two or more coils which may operate in either series or parallel relation; or the booster transformer may be likewise constructed with two or more primary coils which may be operated in either series or parallel relation, or taps may be provided either on the primary or the secondary windings of each phase; or the primary windings may be connected between the standard low voltage terminals of the power transformers in star or delta relation so as to vary the induced voltage in the booster transformer.

My invention further contemplates the use of switches so as to change the direction of the current through the windings of the booster transformer; that is my invention contemplates either adding to or subtracting from voltage the standard voltage between the power transformer terminals.

In one modification, my invention contemplates so constructing the windings of the booster transformer, either the primary or the secondary windings, so that a portion of the winding can be connected in parallel with another portion or so that these two portions can be connected in series, this change being accomplished by the means of a double throw switch. This change in connection from parallel to series of the said portions of windings would result in a change in the induced voltage through these

portions of the primary winding or would change the secondary terminal voltage of the booster transformer; if the portions are on the secondary side. In either case the improvements make a very efficient arrangement of windings for voltage change. This special feature of my invention is not limited to ordinary transformers but may be used in induction furnaces for varying secondary induced voltage around the core of the furnace transformer.

My invention is therefore not limited to voltage changing transformers but includes voltage changing connections for induction furnaces.

Another feature of my invention relates to the means of changing the voltage between different taps on either the primary or secondary windings of the voltage regulating transformer and this feature relates more particularly to the combination of a special switch in combination with a reactance whereby when two taps of the transformer windings are short-circuited through the special switch the reactance will serve to limit the current during such short-circuited period.

Another feature of my invention relates to the location of the booster transformer secondary windings whereby the booster has a neutral point, and the separate phases of a three-phase booster are connected between the neutral point and one terminal of each secondary winding of the three-phase transformer secondaries.

These and other features of my invention will be more fully described with reference to the accompanying drawings.

Fig. 1 is a diagrammatic view of a three-phase transformer showing connections from it to the electrodes and also to a low voltage source of three-phase current. For example, 220 volts three-phase circuit.

Fig. 2 is a view of the arrangement of the booster transformer windings in series with each line to the three electrodes of a three-phase furnace and showing a diagram of the switching arrangements for varying the voltage applied between the electrodes.

Fig. 3 is a wiring diagram of a three-phase transformer showing special connections and switching arrangements for varying the several voltages induced in the windings or supplied by this transformer device.

Fig. 4 is a diagram of the transformer circuits and switch connections of a three-phase induction furnace.

Fig. 5 is a diagram of the connections of a three-phase transformer system to the electrodes of a three-phase furnace and showing the arrangement of the booster transformer connections for voltage control.

Fig. 6 is a diagram of an arrangement of secondary windings or a booster transformer such as might be used in one of the phases

of the transformer system shown in Fig. 5.

Fig. 7 is a wiring diagram showing the connections for changing the direction of current in one primary winding of a booster transformer.

Fig. 8 is a diagram of the arrangement of switches and windings for changing from delta to star or star to delta arrangement of the separate phases.

10 Fig. 9 is a diagrammatic view to illustrate the approximate relation of the secondary voltages between a neutral point and each of the three electrodes of a three-phase furnace with the transformer secondaries in 15 star and without any added or subtracted voltage of a booster transformer.

Fig. 10 is a diagrammatic view showing in a relative way the relationship and the amount of secondary induced voltages not 20 only of the standard power transformer secondaries but also of the secondaries of the booster transformer which when added to them would give the relative value of the 25 electrode voltages when the booster transformer voltages are added to those of the standard power transformers, all being in star connection.

Fig. 11 shows the direction and value of the secondary voltages of a three-phase booster transformer when the direction of the induced voltages is opposite to that shown in Fig. 9.

Fig. 12 illustrates the direction and value of the secondary voltages on the electrodes 35 in case the booster voltages are subtracted from the transformer voltages instead of added to them.

Fig. 13 is another diagram of phase voltages of a booster transformer; and Fig. 14 40 is still another diagrammatic view of the phase relations and voltages in such a system.

Fig. 15 is a view of a modification of my invention for changing the furnace voltage 45 without breaking the circuit.

Referring now to Fig. 1, there is shown in this figure the wiring diagram to illustrate the various connections which may be obtained by use of an auto transformer in 50 connection with an electric furnace. For purposes of illustration, the current supply may be considered as 220 volts three-phase from suitable power transformers to supply the necessary power for the operation of 55 the electrodes of a three-phase electric furnace. The power supply is indicated at 1. A three-pole double throw switch is provided for connecting either of two sets of taps on the primary windings of the transformer with the power circuit. as might be required for the operation of the furnace.

An intermediate tap, like 17, may be provided for each phase, and a special below 5 normal tap, like 19, would be provided for each phase, and any of the two taps on the primary part of a given phase might be connected to the double throw switch for the purpose of changing from one relatively higher 10 voltage to one lower voltage. It is to be understood, however, that a switch might be provided which would change from any one to any other of the primary taps of one phase instead of a double throw switch 15 which only connects one or the other of a pair of taps.

Referring now to Fig. 2 I have shown here 20 another arrangement for the control of voltage on the electrodes of a three-electrode furnace. The electrodes are shown at 47, 48 and 49. Three lines, 55, 54, and 53, bring current from the secondary terminals of a three-phase transformer system for the said electrodes. In between the electrodes and 25 transformer terminals in each phase is placed a secondary of a booster transformer. These secondaries are indicated at 44, 45 and 46. That is, the line 55, coming from one terminal of the transformer leads to a terminal 30 of a secondary winding of the booster transformer 44 and from this secondary the current then is led through the conductor 52 to the electrode 47; and similarly with the other phases. Each phase of the booster 35 transformer system is provided with a primary and a secondary. The primary winding for the booster phases indicated at 44 is shown at 41. For the secondary 45 there is a primary 42; and for the secondary 46 there 40 is a primary 43.

The primary windings of these three booster transformers may be connected by means of double throw switches, 62, 63 and 64, between the lines supplying current to 45 the electrodes, or in other words, between the three secondary terminals of the three-phase transformer system supplying power to the electrodes. These double throw switches serve to change the direction of the induced 50 current through the primary windings of the booster transformers. These booster transformers may be separate from each other, that is, each primary and secondary of a booster may be an individual transformer by 55 itself, or the three may be combined as a three-phase booster transformer.

In the operation of the electrodes in accordance with the arrangement shown in Fig. 2 when the double throw switches are 60 thrown in one direction the induced voltage in the secondary of the booster transformer will add to the voltage between the electrodes and when the double throw switches are thrown in the other direction 65 the induced voltage in the booster secondary

will be such as to subtract from the electrode voltages between electrodes.

It is pointed out that these primaries are connected in delta relation between the lines furnishing current to the electrodes, and as 70 referred to further on, these primaries may be connected in either star or delta relation in accordance with the requirements. If the power transformer secondaries be connected in closed delta relation, then these booster 75 transformer primaries may be connected, as indicated in Fig. 2, but they may also be connected in star relation as referred to elsewhere in this specification.

Fig. 3 shows a combination three-phase 80 transformer system with primary connections to the power line and with secondary connections to the electrodes. The three phases here shown are connected as auto-transformers. The primary windings are 85 provided with separate coils or sets of coils so that a portion of the primary may be operated in either series or parallel relation with another similar portion of the same primary. This will be described with regard 90 to the left-hand winding. The three power lines which supply current to the auto-transformer are shown at 92, 93, and 94. The primary has two separate sets of coils, one end of one being shown at 89 and one end of the other at 83, and the opposite ends at 86 and 80 respectively. These windings may be thrown in series by throwing the switch 95 down and they may be thrown in parallel by throwing the switch 95 up. The other two 100 phases are provided with a similar arrangement of coils and switches, the switches being shown at 96 and 97.

The connections to the three electrodes of the furnace are shown at 74, 75 and 76. The 105 other taps, 79, 78 and 77, may be connected with the electrodes instead of the higher voltage taps last mentioned. The three separate phases are shown at 71, 72 and 73 and are here shown connected in star relation. 110

Fig. 4 is a transformer system which may include a single turn secondary heating circuit which might be an induction furnace. The transformer system is connected by means of a switch 111 to a power supply circuit indicated at 112. The system is provided with two transformer cores, 121 and 122, which may serve to operate in open delta relation. Two primary windings are shown at 101 and 102. Additional primary windings are shown at 115 and 116 and these may be operated in either series or parallel relation to each other by means of the switch 119, and they may be connected through the switch 113 to the other portion of the coil 120 101. The windings 101 and 102 may be connected in open delta relation to the power supply. 125

The circles 123 and 124 indicate the single turn secondary circuits which might be in- 130

duction circuits around a leg of the magnetic cores.

- This transformer device may be operated to control and regulate the single turn induced secondary voltage in the secondary circuit 123 by means of the switch 119. When the switch 119 throws the two coils 115 and 116 in parallel then the number of turns of winding between the line 105 and the line 108 will be less than when the two coils 115 and 116 are thrown in series by throwing the switch 119 in the opposite direction. In this way the single turn voltage induced in the primary winding may be increased or diminished. When it is desired to lower the single turn voltage of the primary and therefore of the secondary more turns would be put in circuit between the conductors 105 and 108.
- 20 The single turn induced voltage in the other secondary 124 may be regulated and controlled in the same way as just described. The voltage in either phase may be regulated and controlled independently of that in the other phase.
- 25 When the two phases, that is the two separate primary windings of the transformers, are connected in open delta as would be the case when the switches 119 and 120 and 106 and 111 are closed, then a certain single turn voltage would be induced in each phase, and then by opening the switch 106 but leaving the other switches closed, the two primaries would be thrown in series with each other and therefore the total number of turns between two conductors like the conductors 108 and 109 would be doubled and the single turn voltage correspondingly reduced.

- Referring now to Fig. 5 I have shown here another system of transformer connections and the diagram in this figure represents the three electrodes of an electric furnace shown at 125, 126 and 127 connected through reactance coils shown at 133, 132 and 131 to the secondary terminals of three transformer secondaries. These power transformers are represented in the diagram at 135, 134 and 136. These transformer secondaries may be of 70 volts each for example. When they are connected in star relation the voltage between electrodes on open circuit would be roughly 121 volts (70×1.73). This diagram in Fig. 5 shows a secondary of a booster transformer connected between one end of each power transformer and the neutral point of the secondary system. These booster secondaries are indicated at 138, 137 and 139 and they are connected together in star relation. Each booster secondary might furnish 12 volts for example in addition to the 70 volts of each power transformer secondary and then the voltage between electrodes would be approximately 141 volts (82×1.73). Referring to Figs. 9 and 10, if the power transformers were connected in star without the booster voltage being added

the diagram of the voltages of the three transformer secondaries would be somewhat like the diagram shown in Fig. 9; that is the voltage of the secondary 134 would be represented roughly by the line 181 and the voltages of the other two secondaries 135 and 136 by the lines 182 and 183. Now if the booster transformer secondaries are inserted as shown in Fig. 5 then the voltages of the separate phases and separate secondaries would be roughly as indicated in Fig. 10. That is the voltage of the secondary 134 of the power transformer which would be 70 volts is represented by the line 184, and the voltage of the booster transformer 137 is represented by the line 187 and if these two be added together the sum of 70 volts and the 12 volts would be roughly 82 volts between the neutral point and the electrode. It is understood that this diagram does not take account of the disturbance of the phase relations resulting from the passage of current through the reactances in circuit. The voltages in the other secondaries would be indicated in Fig. 10 as already mentioned for the secondaries 134 and 137.

The booster transformer secondaries 137, 138 and 139 could be short-circuited by means of a knife switch or other suitable switch so that the transformers would be connected directly together in star on their secondary side without any effect from the booster transformer. When the secondaries of the booster transformers are short-circuited the primaries must of course be short-circuited or disconnected in such a manner as not to short-circuit the power transformer through the secondary windings. Instead of short-circuiting the secondaries the primaries could be disconnected from the lines which supply the inducing current and they could be short-circuited instead of the secondary windings being short-circuited but in such event there is an increased loss due to the passage of the current between the neutral point of the system on the secondary side through the booster secondaries so that in certain cases it may be desirable in order to increase the efficiency to use switches on both the primary and secondary windings of the booster transformer system.

The direction of the induced voltage in the secondary transformer windings may be reversed by reversing the direction of the connection of the primary windings between the lines. For example, referring to Fig. 7 if the primary of the booster transformer is indicated at 162 and the three-phase circuit lines at 165, 166 and 167, then the primary winding 162 may be connected between the lines 165 and 166 in either direction by reversing the switch 164. For example, when the switch 164 is thrown up then the terminal 163 of the primary connects with the line 165 but when the switch 164 is thrown down

then the same terminal 163 is connected with the other line 166 and at the same time this double throw, double pole switch reverses the connection of the other terminal 162. In other words, this Fig. 7 shows a diagram of the change in the direction of the current through the primary winding of a booster transformer.

Referring now back to Fig. 5, there is shown the three booster primaries at 140, 141 and 142 and these are connected together in star relation with each other and with the three lines connecting with the electrodes. For example, the power transformers supply 140 volts to the electrodes and the primaries of the booster transformers are connected between these three lines shown at 128, 129 and 130. I have shown the connection between these lines and the three transformers indicating that the number of turns of each primary may be varied so that the line voltage applied to these primaries may be regulated and controlled as desired. For example, in the diagram shown in this Fig. 5 when the voltage between the electrodes is lowered then it may be desirable to change the number of turns on the primaries of the booster transformers so as to regulate the amount of the secondary voltage of the booster transformers.

Although I have shown the booster transformer primaries connected in star it is understood that they may be connected in delta between the lines or they may be thrown from star to delta in order to change the secondary voltage of the booster transformer or their connections to each other and to the lines which may be controlled and regulated in any manner I have shown in the several figures in the drawings.

When it is desired to have the secondary booster voltage buck the power transformer voltage then I may reverse the direction of each of the primary windings so that the 12 volts, for example, instead of being added to the 70 volts of each phase of the power transformers would be subtracted from that 70 volts with the result that the voltage between the neutral point and each electrode would be approximately .58 volts and the electrode voltage would then be approximately 101 volts instead of 140 volts when the booster transformer voltages were added to the power transformer secondary voltages. This relation of secondary voltages between electrodes is further shown diagrammatically in Fig. 12. The net voltage between the neutral point and the electrodes is indicated by the lines 193, 194, 195. That is, instead of the voltage corresponding to the line 181 in Fig. 9 the line 193 is shorter by the amount of the voltage induced in the booster transformer but induced in the direction opposite to that of the secondary power transformer voltage 193. The voltages of the

other phases are shown at 194 and 195 respectively. The diagram of the primary windings is then represented in Fig. 11 where the voltage in the primary 142 is represented by the line 190 and before reversing the direction of connection of this particular phase the voltage would be represented by the line 183 in Fig. 9.

I have shown in Fig. 8 a diagram of connections for changing the booster primaries from star to delta. The three primary windings are indicated at 170, 171 and 172. The double throw switch 176 serves to connect these separate windings in either star relation by connecting them together by throwing the switch 176 down to the point 177, or if the switch 176 is thrown up it connects the primaries in delta relation with the lines 178, 179 and 180.

When this switch 173 is connected with the line 174 and the three phases are connected in star through the switch 176 then the transformer winding 170 is in circuit but if this transformer winding 170 is disconnected by opening the switch 173 and closing it to the point of 175, then this particular phase would be short-circuited. The other two phases, 171 and 172, may be likewise provided with such a switching arrangement so that they can be short-circuited. That is, if it is desired to neither add to nor subtract from the power transformer voltage these booster transformer primaries may be short-circuited in the manner just described so that there is no voltage induced in them and then the booster transformer secondaries may likewise be short-circuited in order to save the loss of power from the current flowing through them in the operation of the power transformers.

I have shown in Fig. 6 one arrangement of the secondary windings of the booster transformer. I have shown here two secondary coils having terminals 151, 152, 153 and 154. These coils might represent single turns. They might be, for example, 6 volts each with certain primary connections to give this secondary induced voltage. They may be connected in series so as to give a total of 12 volts, or they may be connected in parallel to give greater capacity at only 6 volts. Still again, the induced voltage may be varied by means of the primary connections of the booster transformer.

With further reference to Fig. 3, I have shown three single turn circuits which represent diagrammatically the secondary circuits of an induction furnace, one for each phase. These are shown at 74^a, 75^a and 76^a. I have done this merely to indicate that the voltage regulating system shown and described with reference to Fig. 3 may be used for the regulation and control of the voltages in the three separate circuits of the three phase induction furnace in the same manner.

as has been described for the regulation of the voltages in the electrode circuits connected with the taps 74, 75 and 76. It is further understood that the operation of the booster transformer system shown in Fig. 2 may be in accordance with that described in other figures. That is, the primaries may be connected as shown in Fig. 8, for example, or in any other way illustrated or described herein.

In Fig. 15 I have shown one means of changing connections between different taps and a line. In this figure I have shown a transformer winding which may be either primary or secondary at 210. This winding 210 is provided with a suitable series of taps like the taps 203 and 204 connecting with a part of the winding shown at 202, that is, connecting with different coils of this part of the winding. A switch 209 is provided and this switch has two connecting conductors, 206 and 208. This switch is mounted on a suitable pin so that it may revolve about this pin by means of the handle 209 and connect with different taps like that shown at 205. The two terminals 206 and 208 are connected together by means of a suitable reactance 207 and this reactance may in turn be connected with the line which it is desired to connect with any given tap. In the operation of this switch when it is shifted between the taps of a transformer winding if two taps are short-circuited they are short circuited through the reactance 207 and this may be sufficient to prevent any undesired heating as a result of short-circuiting two different coils of the transformer winding. The switch may thus be shifted between any of the taps and when left in connection with any one tap it is in such position that both the switch terminals 206 and 208 will rest on the same tap, as for example, 205, so that there will be no injurious short-circuiting of the winding.

Referring to Fig. 13 and Fig. 14, I have shown here the relative directions of the induced voltages in a three-phase booster transformer system when the primaries are connected in delta and the secondaries in star. Thus, if the line 196 represents the direction of the primary induced voltage then the secondary induced voltage for the corresponding phase would be along the line 199 of Fig. 14 although opposite in direction. These two diagrams in Fig. 13 and Fig. 14 do not show the voltage values which might be obtained in such a system.

It is understood also that a switch like the switch 173 in Fig. 8 may be used in connection with the secondary windings. For example, such a switch might be provided in connection with the secondaries like that at 137 in Fig. 5 so that when the primaries are disconnected from the line

and short circuited, the secondaries may 65 also be short circuited if desired.

It is understood that the improvements which I have described in this application may be combined in various ways without getting away from the invention.

In order that the method of using this apparatus of this invention cannot be misunderstood, I will describe how, for example, the apparatus shown in Fig. 5 may be used for melting and refining basic steel, 75 that is for melting a charge of steel scrap in a basic lined hearth and refining or treating the molten steel after it is melted. The cold steel scrap would be charged into a furnace into which the three electrodes 125, 80 126 and 127 enter. The transformers and booster apparatus would be connected to give, for example, 120 volts between electrodes for melting the charge and heating 85 the metal. This voltage between electrodes might be obtained by the following combination. The three power transformers have their secondaries connected in star, one terminal of each secondary being connected to the neutral point. The neutral point may 90 or may not be grounded. The booster secondaries are placed one in series with each power transformer secondary. If the power transformer secondary be 70 volts and the booster normally 12 volts, then in order 95 to use the 120 volts between electrodes, the booster transformer secondaries would be short circuited and the power transformers connected in star would give the 120 volts between electrodes, or 121 volts more nearly. 100 Then if a lower voltage is desired for finishing the heat a voltage between electrodes of approximately 100 volts open circuit could be used. This voltage would be obtained by connecting the booster transformer primaries to the power transformer secondary terminals giving 120 volts between terminals and the proper taps on the booster primaries would be selected to give about 12 105 volts which voltage would buck the 70 volts 110 of each power transformer,—giving a net voltage of about 58 volts between each electrode and the neutral or approximately 100 volts between electrodes. The change of voltage may be accomplished by a double 115 throw switch as indicated in Fig. 8 operating on the booster primaries. When operating at a voltage of 120 between electrodes the switch would short circuit the primaries of the boosters; and at the same time the secondaries could be also short circuited by suitable switches or by a single three pole switch. Then when 100 volts is wanted the primary booster switch would be thrown 120 the other way and would so connect the booster primaries to the 120 volt 3 phase circuit as to produce a voltage of 12 volts 125 in each secondary to buck the 70 volts.

In case the power transformers are connected as shown in Fig. 5 so that the booster secondaries are between them and the neutral point then the booster primaries can be energized from the power transformers and a single double pole double throw switch used for each booster primary,—so that the booster primaries would not be subject to the voltage change of the electrodes. The arrangement in Fig. 2 shows this kind of a connection with a standard low voltage power circuit where the booster primaries are connected back of, that is on the power supply side of the electrodes:

15 It is understood that the voltage may be changed at any time desired during the metallurgical process. For example it may be desired to start with a high voltage and use it until the bath and charge become sufficiently hot to necessitate pulling out the arcs in order to lower the development of energy in the arcs. This pulling out of the arcs exposes the walls of the furnace unnecessarily to the heat of the long arcs and the voltage 20 may be changed before the arcs have to be pulled out and the voltage may be changed so as to maintain the power high or low and at same time keep the arcs within approximately constant length.

30 It is also understood that my present invention may be applied to an induction furnace or to other types of resistance furnaces; and also that the change from one connection of taps to another may be made by any 35 suitable switching arrangement or means of changing connections. However, the modification of my invention whereby the applied voltage can be changed without cutting off the power from the furnace, that 40 is by using the device shown in Fig. 15, and this may be used either in an induction furnace or in an electrode furnace.

What I claim is:

1. In combination with the electrodes of an electric furnace, a transformer system comprising a plurality of secondary windings connected together in series relation, a conductor for carrying the current from said secondary windings to an electrode, and means for regulating the relative value and direction of induced voltage in the separate secondary windings for controlling the voltage between the outer ends of the two windings when connected in series.
- 55 2. In combination with electrodes of an electric furnace, a secondary transformer winding connected in series with an electrode, a separate secondary transformer winding also in series with said first secondary, and means of inducing voltage in the separate secondaries whereby the smaller secondary voltage is either added to or subtracted from, that is boosts or bucks the voltage of the main secondary.
- 60 65 3. A system for controlling the voltage

between the electrodes in an electric furnace comprising a main transformer and a booster transformer with their secondary windings in series and means for controlling relative direction and value of the induced voltage whereby the smaller secondary voltage may be added to or subtracted from the larger voltage.

4. The combination with an electric furnace of means for supplying alternating current thereto at varying voltages, said means comprising a plurality of power transformers having their secondaries connected with the furnace terminals and a booster transformer in series between each power transformer and a furnace terminal, and means for regulating the direction and value of the induced voltage in the booster secondary.

5. The combination with an electric furnace of means for supplying alternating current thereto, and means for connecting sections of a transformer winding together in series or parallel relation and means for connecting said sections in series with another section for varying the induced voltage of the transformer.

6. In combination with an electric furnace, a source of poly-phase alternating current power for supplying current to the terminals of said furnace, and a booster transformer having a secondary winding in series between one terminal of each phase of the furnace and a corresponding phase of the supply circuit and means for controlling the relative direction and value of the secondary voltage in each phase of the booster transformer.

7. In combination with an electric furnace, a source of alternating current power for supplying current to the terminals of said furnace, a booster transformer having a secondary winding in series between the furnace terminal and the power supply, a primary winding for said booster transformer, and a switch for controlling the direction of current flow through the primary of said booster transformer.

8. In combination with an electric furnace, a source of three phase alternating current, a three phase booster transformer having its secondary windings connected in star between a neutral point and the three secondary terminals of three power transformers, the other secondary terminals of said power transformers leading to the furnace terminals and means of controlling the direction and value of the secondary booster voltages.

9. In combination with an electric furnace, a source of three phase alternating current for supplying current to the furnace terminals, a booster transformer having a secondary in series between each furnace terminal and the corresponding phase of the power supply and means of connecting the

booster primaries in star or delta relation to change the booster secondary voltage.

10. In combination, an electric furnace, a transformer system having taps for supplying different voltages to the furnace terminals, a switch mounted to connect with different taps of the same phase, and means for limiting the short circuit current between two taps during the shifting of the switch from one tap to another.

11. In combination with an electric furnace, a transformer having taps for different voltages, a switch mounted to change connection from one tap to an adjacent one, said switch comprising a current limiting device which operates to limit the short circuit current between two taps during the period when they are short circuited thru the switch connections in shifting the switch.

12. In combination with an electric furnace, a transformer having taps, a switch for changing connections from one tap to another without breaking the circuit to the furnace, said switch being mounted to make connection with two taps at the same time during movement from one to another, and a current limiting device in combination with said switch to limit the short circuit current thru the part of the winding short-circuited during movement of said switch.

13. The method of operating an electric furnace which method consists in connecting a winding of a transformer in series with a terminal of the electric furnace and regulating the circuit connections to control the direction and amount of the induced voltage in combination with the voltage of the supply circuit.

14. In combination with an electric arc furnace for the manufacture of iron or steel, 40 said furnace requiring different voltages on the electrodes for its operation, a transformer, a winding thereon, a series of taps on said winding for inducing the desired voltage to be applied to said electrodes, and a 45 switch for changing from one voltage to another without breaking the circuit supplying current to the electrodes or interrupting the arc.

15. In combination with an electric furnace having arcing electrodes, a transformer supplying current to the electrodes and another transformer winding in series between an electrode and the transformer first mentioned, and a primary winding for the 55 series transformer, and switch means for connecting this primary to the circuit between the first mentioned transformer and the electrodes when thrown in one direction and for short circuiting the primary winding of the 60 series transformer when thrown in another direction.

16. In combination with an electric furnace having arcing electrodes, a three phase transformer for supplying power to the furnace and a second transformer having a secondary winding in series with each electrode and having a primary which can be short-circuited by switch means and which can be connected to the electrode side of the series 65 transformer secondary winding so as to cause the voltage thereof to oppose that of the power transformer.

In witness whereof, I hereunto subscribe my name this 15th day of May, A. D. 1923.
ALBERT E. GREENE.
